UNITED STATES PATENT OFFICE

EDWIN F. HULBERT, OF OWEN, WISCONSIN, ASSIGNOR TO THE MASTER PACKAGE CORPORATION, OF OWEN, WISCONSIN, A CORPORATION OF DELAWARE

STAPLING DEVICE.

Application filed February 17, 1928. Serial No. 255,087.

The invention relates to stapling devices.

The object of the invention is to provide a stapling device more particularly designed to set and clinch staples securing the removable head to the siding of a container.

By the present invention one end of the staple is driven into the fibre siding of the container while the other end of the staple is turned over a bead formed on the removable head of the container and driven into the fibre forming a part of said head.

The invention further consists in the several features hereinafter set forth and more particularly defined by claims at the conclusion hereof.

In the drawings Fig. 1 is a side elevation view of a device embodying the invention, part of one of the handles being broken away, the device being shown in its final position;

Fig. 2 is a view similar to Fig. 1, parts being broken away and parts being shown in section, with the device in loading position;

Fig. 3 is a front elevation view of the device embodying the invention;

Fig. 4 is a detail sectional view taken on the line 4—4 of Fig. 2;

Fig. 5 is a side elevation view of the staple upon which the tool acts.

Referring to the drawings, the numeral 6 designates the body of the tool, which is provided with a longitudinally extending slot 7 which is open from its lower end to a bead-engaging groove or hook portion 8 having a staple-bending-and-forming groove 9 therein.

A sliding member or plunger 10 is mounted to slidably reciprocate in the slot 7 and has a longitudinally extending groove portion 11 alining with the groove 9 and merging into a staple-end-receiving pocket 12. The plunger 10 is reciprocated by means of a bifurcated head 13 whose bifurcations are formed into the shape of companion cams 45 between which the plunger 10 is mounted and to which it is pivotally secured by a pin 14 passing through an opening in the plunger and set at its ends in the cams, said head being formed integral with or secured to a

handle 15. Swinging of the handle 15 from the position shown in Fig. 2 to that shown in Fig. 1 causes a forward movement of the plunger 10 so that when a staple, such as shown in Fig. 5 and designated by the number 16, is inserted in the space provided

by the grooves 9, 11 and 12 and the device is hooked over the beaded edge 17 of the removable head 18 associated with the siding 19 of a container and the handle is turned to move the plunger 10 upwardly, the staple 60 will be driven at its lower end 20 into the siding 19 of the container and the pressure exerted longitudinally of the staple by the plunger will, through the cooperation of the forming die 9, bend the upper end 21 of the 65 staple over the bead and embed it into the top 18 of the head.

As shown, the handle 15 swings toward the inside of the container in affixing the staple and in this case the handle 22, affixed to the top 6 and extending laterally therefrom, is pressed on by the operator while affixing the staple so as to secure an efficient, embedded engagement of the lower end 20 of the staple with the siding. It is possible, of course, to 70 reverse the position of the handle from that shown in Fig. 1 and in that way dispense with the handle 22, but in doing so such severe side-thrusts are created against the side of the container adjacent the portion being 75 acted upon by the lower end of the staple that it tends to crush the siding of the container and, therefore, the handle 15 has been arranged as shown and associated with the handle 22.

It will be noted from Fig. 1 that the hook portion 8 fits over the bead 17 formed on the head of the container and that the portion of the body adjacent the groove 11 depends from the side of the container so that the 80 container forms a rest for the tool and interlocks therewith over the bead.

While the association of the staple with the particular type of container herein shown does not form a part of the present invention, which is directed to the tool, it will be noted that by applying the staple in this way an efficient, locking connection is had between the body of the container and the removable head since the staple engages a reinforcing 90 head-band 23 and the lower pointed end 20 grips into the siding adjacent the lower edge of a reinforcing metal mouthband 24 surrounding the siding of the container.

With a tool of the character above described several staples may be driven into the siding and top of the container, suitably spaced about its periphery, and the cover therefore securely locked thereto.

I desire it to be understood that this in- 110

vention is not to be limited to any particular form of arrangement of parts except in so far as such limitations are included in the claims.

5. **What I claim as my invention is:**

1. A stapling device for affixing staples to containers having covers provided with beaded edges, comprising a member provided with a hook portion engageable with the beaded edge of said container cover, said member having a staple-receiving groove in its hook portion, a movable plunger associated with said member and having a staple-receiving groove and cooperating therewith to affix the ends of the staple in locking engagement with said cover and the side of the container, and a manually operable cam associated with said plunger and member for moving said plunger to set the staple.

15. to affix the ends of the staple respectively over the bead of the container head bead and into the side of the container, and means for moving said plunger to set the staple.

2. A stapling device for affixing staples to 20 containers having covers provided with beaded edges, comprising a member provided with a hook portion engageable with the beaded portion of said container cover, said member having a staple-receiving-and-forming groove in its hook portion, a movable plunger associated with said member and having a staple-receiving groove and cooperating therewith to bend the upper end of the staple over the beaded edge of said cover and 25 affix the ends of the staple respectively into the head of said container adjacent said bead and into the side of the container, and means 30 for moving said plunger to set the staple.

3. A stapling device for affixing staples to containers having covers provided with beaded edges comprising a member provided with a hook portion engageable with the beaded edge of the container, said member having a staple-receiving groove in its hook portion, a movable plunger associated with 40 said member and having a staple-receiving groove and cooperating therewith to affix the ends of the staple in locking engagement with said cover and the side of the container, and a manually operable cam associated with 45 said plunger and member for moving said plunger to set the staple.

4. A stapling device for affixing staples to containers having covers provided with beaded edges comprising a member provided with a hook portion engageable with the beaded edge of the container, said member having a staple-receiving groove in its hook portion, a movable plunger associated with 50 said member and having a staple-receiving groove and cooperating therewith to affix the ends of the staple in locking engagement with said cover and the side of the container, a manually operable cam associated with said plunger and member for moving said plunger 55 to set the staple, and a lateral extension on said member forming a handle for holding said member against side thrust movement of said cam.

In testimony whereof, I affix my signature.
EDWIN F. HULBERT.
